US0D1111380S

(12) **United States Design Patent** (10) **Patent No.:** **US D1,111,380 S**
(45) **Date of Patent:** **** Feb. 10, 2026**

(54) **OUTSOLE BOTTOM**

(71) Applicant: **Skechers U.S.A., Inc. II**, Manhattan Beach, CA (US)

(72) Inventor: **Savva Teteriatnikov**, Venice, CA (US)

(73) Assignee: **Skechers U.S.A., Inc. II**, Manhattan Beach, CA (US)

(**) Term: **15 Years**

(21) Appl. No.: **29/984,318**

(22) Filed: **Jan. 14, 2025**

Related U.S. Application Data

(63) Continuation of application No. 29/964,430, filed on Sep. 23, 2024.

(51) **LOC (15) Cl.** **02-04**

(52) **U.S. Cl.**

USPC **D2/957; D2/953**

(57) **CLAIM**

The ornamental design for a outsole bottom as shown and described.

DESCRIPTION

FIG. 1 is a perspective view of the outsole bottom in accordance with my new design;

FIG. 2 is a right side view thereof;

FIG. 3 is a left side view thereof;

FIG. 4 is a front view thereof;

FIG. 5 is a rear view thereof;

FIG. 6 is a top view thereof; and,

FIG. 7 is a bottom view thereof.

The dash-dash broken lines shown in the drawings represent environmental structure of parts of the shoe and form no part of the claimed design.

1 Claim, 7 Drawing Sheets
